(57) **CLAIM**

The ornamental design for an adjustment plate for observation device for samples such as cells, as shown and described.

DESCRIPTION

FIG. 1 is a front view of an adjustment plate for observation device for samples such as cells of the first embodiment of the present invention;

FIG. 2 is a rear view thereof;

FIG. 3 is an enlarged view showing a portion 3 of FIG. 2;

FIG. 4 is an enlarged view showing a portion 4 of FIG. 2;

FIG. 5 is an enlarged view showing a portion 5 of FIG. 2;

FIG. 6 is a top plan view thereof;

FIG. 7 is a bottom plan view thereof;

FIG. 8 is a right side view thereof;

FIG. 9 is a left side view thereof;

FIG. 10 is a front, top plan and left side perspective view thereof;

FIG. 11 is a rear, top plan and right side perspective view thereof;

FIG. 12 is an enlarged cross-sectional view along the line 12-12 in FIG. 1;

FIG. 13 is an enlarged cross-sectional view along the line 13-13 in FIG. 1;

FIG. 14 is an enlarged cross-sectional view along the line 14-14 in FIG. 1;

FIG. 15 is an enlarged view showing a portion 15 of FIG. 3;

FIG. 16 is an enlarged view showing a portion 16 of FIG. 4;

FIG. 17 is an enlarged view showing a portion 17 of FIG. 3;

FIG. 18 is an enlarged view showing a portion 18 of FIG. 5;

FIG. 19 is an enlarged view showing a portion 19 of FIG. 5;

(Continued)

FIG. 20 is a front view of an adjustment plate for observation device for samples such as cells of the second embodiment of the present invention;
 FIG. 21 is a rear view thereof;
 FIG. 22 is an enlarged view showing a portion 22 of FIG. 21;
 FIG. 23 is an enlarged view showing a portion 23 of FIG. 21;
 FIG. 24 is an enlarged view showing a portion 24 of FIG. 21;
 FIG. 25 is a top plan view thereof;
 FIG. 26 is a bottom plan view thereof;
 FIG. 27 is a right side view thereof;
 FIG. 28 is a left side view thereof;
 FIG. 29 is a front, top plan and left side perspective view thereof;
 FIG. 30 is a rear, top plan and right side perspective view thereof;
 FIG. 31 is an enlarged cross-sectional view along the line 31-31 in FIG. 20;
 FIG. 32 is an enlarged cross-sectional view along the line 32-32 in FIG. 20;
 FIG. 33 is an enlarged cross-sectional view along the line 33-33 in FIG. 20;
 FIG. 34 is an enlarged view showing a portion 34 of FIG. 22;
 FIG. 35 is an enlarged view showing a portion 35 of FIG. 23;
 FIG. 36 is an enlarged view showing a portion 36 of FIG. 22;
 FIG. 37 is an enlarged view showing a portion 37 of FIG. 24;
 and,
 FIG. 38 is an enlarged view showing a portion 38 of FIG. 24. The features shown in evenly-dashed broken lines depict environmental subject matter only and form no part of the claimed design. The dot-dash broken lines in the drawings represent the bounds of the claimed subject matter, the dot-dash lines, themselves forming no part thereof. The dot-dot-dash lines in the drawings depict the boundaries of the enlarged views that form no part of the claimed design.
